UNITED STATES PATENT OFFICE.

GERALD FORDE, OF NEW YORK, N. Y.

ADVERTISING DEVICE.

Application filed June 11, 1926, Serial No. 115,815. Renewed March 4, 1927.

This invention relates to improvements in advertising devices.

The primary object of the invention resides in a slowly revoluble member containing reversible signs which are respectively displayed on opposite sides of the horizontal axis of rotation of the member whereby double the amount of advertising space is provided.

Another object of the invention is to provide a revoluble member containing a plurality of rotatable panels on the opposite sides of which advertising indicia is adapted to be placed, means for automatically reversing the panels on each revolution of the member for respectively displaying the indicia provided on opposite sides thereof, indicia on one side of the panel being displayed on one side of the vertical axis of rotation of the member while the indicia on the opposite side is displayed on the opposite side of said vertical axis.

With these and other objects in view, the invention resides in certain novel construction and combination of parts, the essential features of which are hereinafter fully described, are particularly pointed out in the appended claims, and are illustrated in the accompanying drawing, in which:—

Figure 1 is a perspective view of my improved display apparatus.

Figure 2 is a vertical transverse sectional view on the line 2—2 of Figure 1.

Figure 3 is a vertical longitudinal sectional view through the device.

Figure 4 is a detail perspective view with parts broken away in section to show the automatic releasing means.

Figures 5 and 6 are detail plan views of the opposite sides of one of the panels.

Referring more particularly to the drawings, the reference numeral 10 designates my improved advertising device in its entirety and which includes a base 11 above which a revoluble member 12 is mounted in spaced brackets 13 which rise from the base.

The member 12 comprises a pair of spaced octagonal shaped end plates 14 having a square shaft 15 extending beyond the same and which is provided at its extreme ends with trunnions 15', which are received in bearings provided in the brackets 13. Turnably supported in the end plates in radial arrangement with the axis of rotation of said member are reversible sign members 16 which

correspond in number to the outer flat surfaces of the end plates.

Each sign member comprises a pair of spaced disks 17 which lie flat against the inner sides of the end plates 14, and which support a panel 18 containing different advertising indicia 19 and 20 on the respective opposite sides thereof for display on opposite sides of the axis of rotation of the member upon each revolution of the same. One of the longitudinal edges of each member is weighted as at 21 for a purpose to be presently explained.

For the purpose of imparting rotation to the revoluble member, I provide an electric motor 22 which is mounted on the base 11 adjacent one end of the member and which drives a relatively large gear 23, fixed to the lower end of a vertical shaft 24, journalled in bearings provided in one of the brackets 13. A relatively small bevelled gear 25 is carried at the top of the shaft 24 and meshes with a bevelled gear 26 carried by one of the trunnions 15'. It is obvious that when the motor is turned on, a relatively slow turning motion is imparted to the revoluble member 12.

Mounted on each flat face of one of the end plates 14 are pivoted latch members 28, each of which comprises an arm 29 extending beyond the outer face of the plate, and a finger 30 movable into and out of openings 31 provided in the adjacent disks 17 of the sign members. The openings 31 in each disk are disposed at diametrically opposite points, so that when the fingers 30 are disposed within the openings, the sign members are locked in a position, wherein the panels 18 are disposed parallel to the flat surfaces of the end plates. Contractile springs 32 have one end connected to the respective latch members while their opposite ends are fixedly connected to the end plates, and which springs serve to normally force the fingers into the openings as the same are brought into registration therewith.

Stationarily mounted with respect to the revoluble member are trip arms 33 and 34 respectively mounted on opposite sides of the vertical axis of rotation of said member, and each arm is disposed at a point so as to actuate the latch members just prior to the movement of the sign members into vertical alignment with the axis of rotation of the

revolute member. The free ends of the arms extend into the path of movement of the arms 29 of the latch members to be engaged thereby for releasing the fingers 30 from the openings 31.

In the operation of the sign reversing means, we shall presume that the revolute member is rotated in the direction shown by the arrows in Figures 1 and 2 of the drawings. The panels on the right side of the vertical axis in Figure 2 are held by the latch members with the weighted edges 31 above the horizontal axis of their pivotal connection, so that the indicia 19 is displayed as the respective panels move to a position at approximately 45°, the weighted edge tends to upset the sign members, so that as the latch members respectively engage the trip 33, the fingers 30 are retracted from the openings 31, whereupon the weight 21 will automatically swing the sign member a half revolution, so as to bring the other diametrically opposed opening 31 into register with the finger, at which time the latch member will have moved past the trip 33 whereupon the spring 32 will force the finger into the registering opening and lock the sign in a reversed position. As the sign elements move over to the opposite or left side of the axis of rotation of said revolute member, the indicia 20 on the reverse side of the panel is displayed, at which time the weighted edges are again on a plane above the horizontal axis of the sign members. However, when the latch members respectively move into engagement with the trip 34, the fingers are again retracted, to allow the sign members to swing to a reverse position to again display the indicia 19 on the right side of the vertical axis of the revolute member.

Although the device is shown as being relatively open, it will be appreciated that the same may be enclosed in a casing having opposed windows for displaying the signs as they are brought into consecutive registration therewith.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. An advertising device comprising a revolute frame member, a plurality of radially arranged panels turnably mounted in said frame member and having advertising indicia on opposite sides thereof, automatic

means for reversing said panels to display the respective indicia thereon on opposite sides of the axis of rotation of said revolute frame member upon each revolution of the latter, and co-acting means between said frame member and said panels for locking the same in display positions. 65

2. An advertising device comprising a revolute frame member, a plurality of radially arranged panels turnably mounted in said frame member and having advertising indicia on opposite sides thereof, automatic means for reversing said panels to display the respective indicia thereon on opposite sides of the axis of rotation of said revolute frame member upon each revolution of the latter, co-acting means between said frame member and said panels for locking the same 70 in display position, and releasing means engageable with said co-acting means at intervals in each revolution of said frame member for permitting the operation of said automatic means. 80

3. An advertising device comprising a revolute frame member, a plurality of radially arranged panels turnably mounted in said frame member and having advertising indicia on opposite sides thereof, automatic means for reversing said panels to display the respective indicia thereon on opposite sides of the axis of rotation of said revolute frame member upon each revolution of the latter, and co-acting means between said frame member and said panels for locking the same in display positions, said co-acting means including pivotally mounted spring actuated latch members carried by said frame member, and engageable with the walls of openings provided in said panels. 90

4. An advertising device comprising a revolute frame member, a plurality of radially arranged panels turnably mounted in said frame member and having advertising indicia on opposite sides thereof, automatic means for reversing said panels to display the respective indicia thereon on opposite sides of the axis of rotation of said revolute frame member upon each revolution of the latter, and co-acting means between said frame member and said panels for locking the same in display positions, said co-acting means including pivotally mounted spring actuated latch members carried by said frame member, and engageable with the walls of openings provided in said panels, and arms disposed in the path of said latch members for retracting the same at intervals during each revolution of said frame member. 100

In testimony whereof I have affixed my signature.

GERALD FORDE.
